INVENTOR

George W. Dover
By Horatio E. Bellmore
ATTORNEY

UNITED STATES PATENT OFFICE.

GEORGE W. DOVER, OF CRANSTON, RHODE ISLAND.

TOOL-HOLDER.

1,366,640.

Specification of Letters Patent. Patented Jan. 25, 1921.

Application filed May 10, 1920. Serial No. 380,395.

To all whom it may concern:

Be it known that I, GEORGE W. DOVER, a citizen of the United States, residing at Cranston, in the county of Providence and State of Rhode Island, have invented certain new and useful Improvements in Tool-Holders, of which the following is a specification.

My invention relates to holders adapted to carry tools upon lathes, planers, and the like.

The primary objects of my invention are to afford the use of a plurality of tools of different character in one structure; to render unnecessary a complete disassemblage of the component parts for the substitution of tools; to facilitate a variety of operations of a single structure; to furnish an adjustment for the tools toward and from the work in a horizontal plane, to elevate and depress the tools in any desired degree from the horizontal plane, and to change the angular positions of the tools; to strengthen the interengagement of the parts; to make the attachment of individual tools unnecessary for grinding purposes; and to strengthen and simplify the entire structure.

To these ends the invention consists of a device possessing certain features of construction and relative arrangement of parts hereinafter claimed, one form of said device being illustrated in the drawings and now to be described in detail.

I will now proceed to describe my invention with reference to the accompanying drawings which form a part of this specification, wherein—

Figure 1 is a plan view of my novel holder,

Fig. 2, a section of the same on line 2—2 of Fig. 1,

Fig. 3, a side elevation of the head,

Fig. 4, a section on line 4—4 of Fig. 1, and

Fig. 5, a side elevation of one end of the supporting arm.

Like reference characters indicate like parts throughout the views.

A holder 8 comprises a shank or bar 9 and a flat circular extension or head 10 disposed at an angle to the shank and provided with a central conical or flaring hole 13 therethrough. The inclined wall 14 formed by the opening is provided with vertical corrugations or serrations 15.

A substantially cylindrical hub or adjusting member 16 has a body 17 of reduced diameter near one end forming a rounded an-

nular shoulder 18, whence the hub tapers forming a truncated conical extension 19 provided on its face with longitudinal corrugations or serrations 20 adapted to register with the serrations 15 in the supporting arm. The body of the hub is longitudinally bored forming a cylindrical recess 22. The bore is of less diameter through the conical extension 19 forming an opening or hole 24. Intermediate the recess and hole is a resultant inclined annular shoulder 26. The body 17 has diametrically opposite openings 28 in its sides. Slidably mounted in the hub is a block comprising a cylindrical body portion 30 in the recess of slightly less length than the recess, an annular shoulder 31, and a stem 32 slidable in the bore 24 provided at one end with a thread 33. The member 30 has a diametrical hole 35 adapted to register with the openings 28 of like diameter. A flanged nut 36 or a nut and washer engages the threaded portion of the stem 32 resting against the outer face of the portion 10 of the supporting arm.

Slidably mounted in the hole 35 in the block, and with a running fit in this hole and in the openings 28, is a tubular rod 37 provided at its ends with internal screw threads 38 and 39. Adjacent one end of the rod are diametrically disposed rectangular openings 40 adapted to slidably receive a bit or cutting tool 41. A set screw 42 engages the threads 39 and is adapted to bear against and retain the bit 41. A boring tool comprising a cutter 43, body 44, and threaded shank 45 may be mounted in the other end of the rod, the shank engaging the thread 38. The tool 43 is disposed at a right angle to the bit 41.

In operation a tightening of the nut 36 elevates the block 30 tightening the rod against the hub 16 at the boundary of the openings 28, and simultaneously forcing the corrugations 20 of the conical extension into the corrugations 15 of the flaring opening 13. The firm engagement of the parts is intensified by locating the corrugations upon inclined faces. The tubular tool support 37 may be longitudinally adjusted or may be rotated to any desired angle by loosening the nut. By the same means the body 16 with the support 37 may be radially adjusted. Both the block and the body are separable from the arm 8 by removing the nut.

It will be understood that the recess 22

may be elongated to permit even a greater extent of travel of the member 30. The longer the extent of travel of said member the smaller the passage for the holder 5 through the hole 35 and openings 28. Hence a holder of very small diameter thickness, or of various cross sectional contours, may be efficiently clamped.

I claim:

10. 1. In a tool holder of the character described, a holding member provided with a hole, a rotatable adjusting member in the hole provided with lateral holes, a block upon which the adjusting member is mounted extending through the first hole, a tool support mounted in the block extending through the lateral holes, and means on the extended portion of the block engaging the holding member for simultaneously clamping 15 the support against the adjusting member and securing the adjusting member against the holding member.
20. 2. In a tool holder of the character described, a holding member provided with a hole, a rotatable adjusting member in the hole provided with lateral holes, a block 25 slidably mounted in the adjusting member, a tool support in the block extending through the lateral holes, and means on the block 30 engaging the holding member for simultaneously clamping the support against the adjusting member and securing the adjusting member to the holding member.
35. 3. In a tool holder of the character described, a holding member provided with a hole, a rotatable adjusting member in the hole provided with lateral holes, a block 40 slidably mounted in the adjusting member, provided with a transverse hole, a tool support in the transverse hole and in the lateral holes, and means on the block engaging the holding member for clamping the support 45 against the adjusting member and securing the adjusting member to the holding member.
50. 4. In a tool holder of the character described, a holding member having a tapered hole provided with corrugations, a rotatable adjusting member comprising a body and a tapered extension provided with corrugations engageable with the first corrugations, a block 55 slidably mounted in the body and

extension and projecting through the hole, a tool support in the block, and a nut engaging the extended portion of the block. 55

5. In a tool holder of the character described, a holding member provided with a tapering hole, a rotatable adjusting member comprising a body provided with a central recess and with lateral holes, and a tapering extension seated in the first hole and provided with an axial opening, a block comprising a body slidably mounted in the recess, and a stem extending through the axial opening and the first hole and provided with a thread, a nut engaging the thread, and a tubular tool holder mounted in the body of the block extending through the lateral holes. 70

6. In a tool holder of the character described, a holding member provided with a tapering hole, a rotatable adjusting member comprising a body provided with lateral holes, and a conical extension registering 75 in the tapering hole, a block slidably mounted in the body and extension provided with a transverse hole, a tubular tool support 80 slidably mounted in the transverse hole projecting through the lateral holes and provided at both ends with internal threads, and means on the block engaging the holding member for simultaneously clamping the tool support against the adjusting member and securing the adjusting member to 85 the holding member.

7. In a tool holder of the character described, a holding member provided with a tapering hole, a rotatable adjusting member 90 slidable in the hole and provided with lateral holes, a block slidably mounted in the adjusting member and extending through the tapering hole and provided with a transverse hole adapted to register with the lateral holes, a tubular tool support 95 slidably mounted in the transverse hole and the lateral holes, and provided with internal threads in each end, transverse openings in the support adjacent the threads near one end adapted to receive a bit, a set screw in 100 one end of the holder adapted to engage the bit, and a boring tool threaded in the other end of the bit.

In testimony whereof I have affixed my signature.

GEORGE W. DOVER.
